(57) **CLAIM**

The ornamental design for packaging blank with integrated lid protection, as shown and described.

DESCRIPTION

FIG. 1 is a top oblique view of the first embodiment showing our new design.

FIG. 2 is a top view thereof.

FIG. 3 is a left view thereof.

FIG. 4 is a right view thereof.

FIG. 5 is a front view thereof.

FIG. 6 is a back view thereof.

FIG. 7 is a bottom view thereof.

FIG. 8 is a top oblique view of the second embodiment showing our new design.

FIG. 9 is a top view thereof.

FIG. 10 is a left view thereof.

FIG. 11 is a right view thereof.

FIG. 12 is a front view thereof.

FIG. 13 is a back view thereof; and,

FIG. 14 is a bottom view thereof.

The broken lines in the drawings depict portions of the packaging blank with integrated lid protection that form no part of the claimed design.

1 Claim, 6 Drawing Sheets
